(57) **CLAIM**

The ornamental design for pizza box, substantially as shown and described.

DESCRIPTION

The pizza box provides a stack of containers with a carrying handle for pizzas.

FIG. 1 is a perspective view of a pizza box showing my new design;

FIG. 2 is a left side view thereof; the right side view being a minor image and symmetrical to the left side view;

FIG. 3 is a top plan view thereof;

FIG. 4 is a front view thereof, the back view thereof being a mirror image and symmetrical to the front view thereof; and,

FIG. 5 is a bottom view thereof.
